[57] CLAIM

The ornamental design for a lamp, as shown and described.

DESCRIPTION

FIG. 1 is a front perspective view of a lamp showing a new design.

FIG. 2 is a rear perspective view thereof.

FIG. 3 is a fragmentary front perspective view thereof on a reduced scale, the shade and bulb being omitted for convenience of illustration and the drawer in the base being opened for purposes of disclosure.

The lamp base is shaded to indicate contrast.
